[57] **CLAIM**

The ornamental design for a combined ruler, level and adjustable angle square, as shown and described.

DESCRIPTION

FIG. 1 is a front elevational view of the combined ruler, level and adjustable angle square of the present invention;

FIG. 2 is a rear elevational view of the combined ruler, level and adjustable angle square of FIG. 1;

FIG. 3 is a left side elevational view of the combined ruler, level and adjustable angle square of FIG. 1;

FIG. 4 is a right side elevational view of the combined ruler, level and adjustable angle square of FIG. 1; and,

FIG. 5 is a top plan view of the combined ruler, level and adjustable angle square of FIG. 1; the bottom view being a mirror image thereof.
